CLAIM

The ornamental design for a car seat cover for pet, as shown and described.

DESCRIPTION

FIG. 1 is a rear perspective view of a car seat cover for pet, shown in a flattened configuration, according to my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front and side perspective view thereof, shown in a folded configuration;

FIG. 9 is a side and front perspective view thereof;

FIG. 10 is a bottom and front perspective view thereof;

FIG. 11 is a front and side view shown in an environment of use on the rear seats of a vehicle;

FIG. 12 is a side view thereof; and,

FIG. 13 is a front plan view thereof.

The broken lines in FIGS. 11-13 represent environmental subject matter that forms no part of the claimed design.
